UNITED STATES PATENT OFFICE.

CHARLES T. WESTLAKE, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE TENDER AND CAB CONSTRUCTION.

1,120,873.

Specification of Letters Patent. Patented Dec. 15, 1914.

Application filed July 5, 1913. Serial No. 777,551.

To all whom it may concern:

Be it known that I, CHARLES T. WESTLAKE, a citizen of the United States, residing at the city of St. Louis, Missouri, have invented a certain new and useful Improvement in Locomotive Tender and Cab Construction, of which the following is a full, clear, and exact description, such as will enable others skilled in the art to which it applies to make and use the same, reference being had to the accompanying drawings, forming part of this specification, in which—

Figure 1 is a side elevational view of a locomotive tender, a portion of a locomotive cab and a portion of a car to the rear of the tender, said tender and cab being constructed in accordance with my invention. Fig. 2 is an enlarged side elevational view partly in section of the rear end of the tender. Fig. 3 is a horizontal section taken approximately on the line 3—3 of Fig. 1. Fig. 4 is a rear elevational view of the locomotive cab. Fig. 5 is a front elevational view of the locomotive tender. Fig. 6 is a rear elevational view of the tender.

My invention relates generally to railway car construction and more particularly to the construction of the end portions of a locomotive tender and the rear end of the locomotive cab, the principal object of my invention being to provide comparatively large, strong and rigid bearing surfaces preferably in the form of reinforcing diaphragms or walls at both ends of the locomotive tender and at the rear end of the locomotive cab, which construction is for the purpose of resisting end shocks and crushing strains delivered to the ends of the tender and cab, thus materially reducing the tendency of the cars to telescope in case of collisions and consequently affording the greatest possible degree of safety to the trainmen who are usually stationed upon the engine and tender.

A further object of my invention is to eliminate the entrances or doors of the locomotive cab, thereby making it possible to materially shorten the cab, and where such construction is carried out an entrance opening into the working space at the forward end of the tender, is located in the side wall of the tender near the forward end thereof.

In carrying out my invention I make use of cast metal end frames of the type disclosed

in Patents No. 927,705, dated August 3, 1909, and No. 917,716, dated April 6, 1909, which end frames are rigidly fixed to the underframes of the tender and locomotive cab and applied directly to said end frames are diaphragms composed of wall plates and face plates, which latter serve as points of attachment for the folding or bellows portions of the diaphragms.

To the above purposes my invention consists in certain novel features of construction and arrangement of parts hereinafter more fully described and claimed.

Referring by numerals to the accompanying drawings, 10 designates the underframe of the locomotive tender, the same being of any suitable construction but preferably cast in a single piece and positioned upon the ends of this underframe and fixed thereto in any suitable manner are vertically disposed one piece end frames 11, the same being in skeleton form and of the type disclosed in the patents hereinbefore referred to. The lower portions of the corner posts of these end frames are preferably provided with rearwardly projecting brackets 12 which extend inwardly from the end sill of the ends of the underframe and bear against shoulders on the latter, which shoulders are preferably provided by the formation of integral lugs, such as 13, on top of the side sills of the underframe.

The body of the tender comprises a suitable frame work located on the underframe between the end frames and arranged on said frame work are the usual double walls 14 and sheets or panels such as are necessary to provide coal and water spaces.

Roof plates or sheets 15 form the top of the tender and formed in said top, is an opening 16 into the coal pocket. The end frame at the forward end of the tender is provided with a door opening 17 and applied to the exterior of said front end frame between the uprights at the sides of the door opening and the corner posts or uprights is an end wall plate or sheet 18, the same being preferably formed of heavy sheet metal.

Arranged a short distance away from the plate or wall at the forward end of the tender is an inverted U-shaped diaphragm face plate 19, the same being supported in the usual manner upon buffer stems 20 and ar-

ranged between this face plate and the end wall or diaphragm plate 18 is a diaphragm bellows or flexible wall 21.

Formed in the side wall of the tender body and at the forward end thereof is a door opening 22 opening into the working space 23 at the forward end of the coal pocket in the tender, such arrangement providing an entrance and exit opening for the 10 trainmen who are usually stationed upon the locomotive and tender. Located upon the tender body immediately below this door is a series of steps 24 and arranged on the tender body to the sides of the opening 15 22 are hand rails 25. The one piece cast metal end frame 26 which is located at the rear end of the locomotive cab is provided with a centrally arranged door opening 27 corresponding with the opening 17 at 20 the forward end of the tender and applied to the exterior of this end frame 26 is an end wall plate 28 preferably of sheet metal. Located a short distance from this end wall or plate is an inverted U-shaped diaphragm 25 face plate 29 which is supported in the usual manner upon stems 30 and arranged between this face plate and the end wall plate 28 is a diaphragm bellows or flexible wall 31. The one piece end frame at the rear end 30 of the tender is not provided with a door opening and applied to the exterior of this frame is a solid sheet or plate 32 preferably of sheet metal. Arranged a suitable distance to the rear of this end wall or plate 35 32 is an ordinary diaphragm face plate 33, the same being supported upon suitable stems 34 and arranged between this face plate and the plate 32 is a diaphragm bellows or flexible wall 35. This portion of 40 the diaphragm at the rear end of the tender is adapted to coöperate with a corresponding yielding diaphragm portion 36 upon the forward end of the first car to the rear of the tender. 45 The one piece end frames applied to the tender underframe and the underframe of a locomotive cab combined with the heavy sheet metal plates which form the end walls of the tender and cab provide solid substantial structures at both ends of the tender and at the rear end of the cab, which structures are particularly adapted to resist end shocks and crushing stresses imparted to the ends of the tender and locomotive, 50 thus materially decreasing the tendency of the cars to telescope during collisions.

By locating the entrance and exit opening for the trainmen in the side of the tender it is possible to materially shorten the locomotive cab and by providing the diaphragm bellows between the forward end of the tender and cab the trainmen while at their stations are to a considerable extent protected from dust and cinders and against 55 inclement weather.

It will be readily understood that minor changes in the size, form and construction of the various parts of my improved locomotive tender and cab construction can be made and substituted for those herein shown and described, without departing from the spirit of my invention, the scope of which is set forth in the appended claims.

I claim:

1. A locomotive tender having a one piece end frame at its forward end in which end frame is formed a door opening, an end wall plate applied to said end frame, and a diaphragm face plate applied to the outer face of said end wall plate around the door opening in the end frame. 75

2. A locomotive tender having a one piece end frame at its forward end in which end frame is formed a door opening, an end wall plate applied to said end frame, a diaphragm face plate applied to the outer face of said end wall plate around the door opening in the end frame, and there being a door opening formed in the side wall of the tender immediately adjacent to said end 90 frame. 85

3. In a locomotive tender, an underframe, side walls, a front end wall comprising a one piece end frame in which is formed a door opening, an end wall plate applied to said end frame, a diaphragm face plate applied to the outer face of the end wall plate around the door opening in the front end frame, a one piece end frame applied to the rear end of the underframe, a rear end wall plate applied to said rear end frame, and a diaphragm face plate applied to the outer face of said rear end wall plate. 95 100

4. In a locomotive tender, an underframe, side walls, a front end wall comprising a one piece end frame in which is formed a door opening, an end wall plate applied to said end frame, a diaphragm face plate applied to the outer face of the end wall plate around the door opening in the front end 110 frame, a one piece end frame applied to the rear end of the underframe, a rear end wall plate applied to said rear end frame, a diaphragm face plate applied to the outer face of said rear end wall plate, and there being a door opening formed in one of the side walls of said tender adjacent to the front end wall. 115

5. In a locomotive tender, the combination with an underframe, of one piece end frames positioned upon and fixed to the end portions of said underframe, and end wall plates applied to the outer faces of said end frames and diaphragm face plates applied to the outer faces of said end wall 125 plates. 120

6. The combination with a locomotive tender having vertically disposed reinforced diaphragms at each end, each comprising a one piece end frame, and an end wall plate, 130

- of diaphragm plates arranged adjacent to and yieldingly mounted upon said diaphragms.
7. The combination with a locomotive tender having vertically disposed reinforced diaphragms at each end, each comprising a one piece end frame, and an end wall plate, of diaphragm plates arranged adjacent to and yieldingly mounted upon said diaphragms, and flexible diaphragm members between the diaphragms and diaphragm plates.
8. A locomotive tender having a vertically disposed reinforced diaphragm at each end, each diaphragm comprising a one piece end frame, and an end wall plate applied thereto and a diaphragm face plate arranged adjacent to and yieldingly mounted upon each diaphragm.
9. A locomotive tender having a vertically disposed reinforced diaphragm at its rear end, the same comprising a vertically disposed end frame, and an end wall plate applied thereto and a diaphragm face plate arranged adjacent to and yieldingly mounted upon said diaphragm plates applied thereto and a diaphragm face plate arranged adjacent to and yieldingly mounted upon said diaphragm.
10. In a locomotive tender, the combination with an underframe, of side walls positioned on said underframe, a front end wall comprising a one piece end frame, a front end wall plate and a diaphragm face plate, a rear end wall comprising a one piece end frame, a rear end plate and a diaphragm face plate yieldingly mounted on said rear end frame, a rear end wall plate, and there being a door opening formed through one of the side walls of the tender adjacent to the front end wall.
- In testimony whereof I hereunto affix my signature in the presence of two witnesses, this 30th day of June, 1913.

CHARLES T. WESTLAKE.
